UNITED STATES PATENT OFFICE.

WILLIAM H. MINER, OF CHAZY, NEW YORK.

DRAW-BAR-CENTERING DEVICE.

1,225,154.

Specification of Letters Patent.

Patented May 8, 1917.

Application filed July 6, 1915. Serial No. 38,090.

To all whom it may concern:
Be it known that I, WILLIAM H. MINER, a citizen of the United States, residing at Chazy, in the county of Clinton and State 5 of New York, have invented a certain new and useful Improvement in Draw-Bar-Centering Devices, of which the following is a full, clear, concise, and exact description, reference being had to the accompanying 10 drawings, forming a part of this specification.

This invention relates to improvements in draw bar centering devices.

An object of the invention is to provide a 15 centering device for draw bars of railway cars, which device is so arranged that it will automatically return the draw bar to the central or normal position and is so constructed as to minimize the friction between 20 the centering carriage and the draw bar carry-iron, and also between the draw bar and its support.

In the drawing forming a part of this specification, Figure 1 is an end elevation of 25 a portion of a car underframe, the draw bar being shown in section. Fig. 2 is a longitudinal sectional view taken substantially on the line 2—2 of Fig. 1, and Fig. 3 is a detail perspective view of the frame employed 30 in my improvement.

In said drawing, 10—10 denote center sill or other longitudinal members of the car underframe connected at their outer ends by means of a tie or bracing strap 11. Secured 35 to the sills and strap 11, and depending therefrom is a draw bar carry-iron 12, having a horizontal table portion 13. The carry-iron 12, as shown, is detachably connected to the car underframe as by means of bolts 14.

The draw bar 15 is centered by means of a 40 movable frame 16, shown in detail in Fig. 3. As there shown, the frame 16 comprises a pair of spaced upstanding side walls 17—17, the inner faces of which are oppositely 45 beveled, as indicated at 18—18. On the outer sides of each of the side walls 17, extend outwardly pairs of flanges 19—19, each pair supporting an anti-friction roller 20, mounted on a bolt or pin 21, said rolls 20 riding 50 upon the upper face of the horizontal portion 13 of the draw bar carry-iron. The frame 16 is also provided with depending front and rear walls 22—22 which straddle the draw bar carry-iron 12, and thus prevent 55 the frame 16 from moving longitudinally of the car. At each of its four corners the

frame 16 is provided with depending arms 23—23, the lower ends of which have inwardly projecting lugs or shoulders 24—24, for the purpose hereinafter described. The 60 frame 16 on its front and rear faces is also provided with pairs of outstanding lugs 25—25, in each pair of which is mounted an anti-friction roller 26, the upper surfaces of the rollers 26 extending slightly above the 65 upper edges of the walls 22—22, so that the draw bar bears upon said rollers 26—26. Secured to the underside of the carry-iron 12 is a plate 27, of a substantially wide U shape. Slidably mounted on the plate 27 are two 70 fol- 75 spring followers 28—28, each of said fol- 80 lowers having forwardly and rearwardly ex- 85 tends projections 29—29 at their inner 90 ends, said projections 29 fitting between the lower edges of the walls 22—22 and the 95 shoulders 24—24. Each of the followers 28, on its inner face, is recessed as indicated at 30, to thereby form a seat for one end of a spring 31, the spring 31 being held in proper position by spiders 32 formed on said fol- 100 lowers, as shown most clearly in Fig. 2.

In assembling the centering device, the 105 followers and spring are first inserted be- 110 tween the plate or strap 27 and carry-iron 12, the spring is then compressed and the 115 frame 16 placed over the carry-iron 12, and when in its proper position the followers and spring are released so that the shoulders or projections 29 engage the depending arms 23 of the frame. In this way, it will be seen 120 that the followers and frame are self-locked and accidental displacement of either is pre- 125 vented.

In operation, friction between the draw 130 bar and its support as the draw bar moves 95 back and forth longitudinally is minimized, due to the anti-friction rollers 26—26. Also, in lateral or radial movement of the draw 135 bar, friction between the centering frame and the carry-iron 12 is minimized, due to 140 the anti-friction rollers 20—20.

From the foregoing, it will be seen that I 145 have provided a centering device for draw 150 bars which is of simple construction, easily 155 assembled and disassembled, and wherein the parts are self-locked when in position.

Although I have herein shown and de- 160 scribed what I now consider the preferred 165 embodiment of my invention, yet I am 170 aware that various changes and modifica- 175 tions may be made in the details of construc- 180 tion and arrangement of parts without de- 185

parting from the spirit of the invention, and all such changes and modifications are contemplated as come within the scope of the claims appended hereto.

5 I claim:

1. In a draw bar centering device, the combination with a carry-iron, of a centering frame straddling said iron and slidably back and forth thereon, said frame having depending arms, a spring and spring followers, said followers and arms having interengaging shoulders which, in operative position of the parts, prevent accidental removal of either the frame or the followers.
- 15 2. In a draw bar centering device, the combination with a carry-iron, of a plate secured to the underside of said carry-iron, spring followers slidably mounted on said plate, a spring between said followers, and a frame slidably mounted on said carry-iron, said frame having depending arms on opposite edges of the carry-iron, said arms and followers being provided with interengaging, self-locking means.

3. In a draw bar centering device, the combination with a carry-iron having a plate secured to the bottom thereof, of spring followers slidably mounted on said plate between it and the carry-iron, said followers having forwardly and rearwardly extended shoulders, a spring interposed between said followers, a frame slidably mounted on said carry-iron and straddling the latter, said frame having depending arms at the corners thereof, each arm having a shoulder engaging a shoulder of a follower, anti-friction means interposed between said frame and the carry-iron, and anti-friction means carried by said frame upon which the draw bar is adapted to be supported.

In witness that I claim the foregoing I have hereunto subscribed my name this 5th day of June, 1915.

WILLIAM H. MINER.
